AUTOMATIC DRILLING MACHINE

Aaron Simons, Bronx, N. Y.

Application March 15, 1940, Serial No. 324,028

19 Claims. (Cl. 51—71)

This invention relates to drilling machines or what are better termed automatic drilling machines, and particularly to machines of this kind adaptable for use in the drilling of diamonds, tungsten carbide or other hard materials for use as wire drawing dies; and the object of the invention is to provide a machine of the character described employing a plurality of drill supporting spindles with means for movably supporting workpieces beneath the spindles to intermittently move the workpieces toward and from drills supported in the spindles while rotating the drills at high speed and maintaining the drills in a fixed position; a further object being to provide means for intermittently rotating the supports for the spindles and the workpieces in bringing successive drilling units into a grinding and lubricating position with means for grinding the drills in this position and for dropping a combination lubricant and abrasive into the workpieces automatically; a further object being to provide means for automatically lowering the workpieces and their supports when in the grinding position to give free access of the grinding wheel to the drill to be ground; a further object being to provide means for reciprocating the grinding wheel vertically with respect to the drill in grinding the pointed end thereof, and further to the adjustment of the support for the grinding wheel to control angularity of the grinding upon the drill, thereby adapting the machine for the grinding of all drills utilized in a complete cycle of operation of drilling diamonds or other workpieces; a further object being to provide means for re-surfacing the grinding wheel intermediate predetermined grinding operations; and with these and other objects in view, as will more fully hereinafter appear, the invention consists in a machine of the class and for the purpose specified, which is simple in construction, efficient in use, and which is constructed as hereinafter described and claimed.

The invention is fully disclosed in the following specification, of which the accompanying drawings form a part, in which the separate parts of my improvement are designated by suitable reference characters in each of the views, and in which:

Fig. 1 is a side and sectional view of a machine made according to my invention.

Fig. 2 is an enlarged sectional view substantially on the line 2—2 of Fig. 1.

Fig. 3 is a sectional plan view substantially on the line 3—3 of Fig. 1 with parts of the structure broken away.

Fig. 4 is a sectional detail view substantially on the line 4—4 of Fig. 1.

Fig. 5 is a sectional view substantially on the broken line 5—5 of Fig. 4.

Fig. 6 is a face view of a part of the construction as seen in Fig. 4 looking in the direction of the arrow 6—6.

Fig. 6A is a detail view looking in the direction of the arrow 6A of Fig. 6.

Fig. 7 is a view looking in the direction of the arrow 7—7 of Fig. 3, with parts of the construction broken away and in section.

Fig. 8 is a view similar to Fig. 7 showing the parts in a different position.

Fig. 9 is a face view of the lower end portion of one of the workpiece supporting members which I employ.

Fig. 10 is a sectional detail view substantially on the line 10—10 of Fig. 1 on an enlarged scale.

Fig. 11 is a perspective view of a wobble cam detached.

Fig. 12 is a sectional detail view through a workpiece indicating diagrammatically the manner of drilling a diamond forming part of the workpiece.

Fig. 13 shows detached views of modified points of drilling needles which I employ.

Fig. 14 is an enlarged detail view of a part of the construction shown in Fig. 1 of the drawings; 30 and

Fig. 15 is an enlarged detail view of a part of the construction shown in Fig. 1.

For the purpose of describing one use or adaptation of my invention, I will refer to its use in 35 the drilling of diamonds to produce what are commonly known as drawing dies. It will be understood, however, that the machine may be utilized in performing drilling operation in workpieces of various kinds and classes and especially where it

40 is desirable to successively drill a workpiece with drilling tools having different angles whereby in a successive series of drilling operations a predetermined tapered hole or socket may be formed in a workpiece, and one having a relatively fine 45 pointed end so as to adapt the resulting workpieces for drawing strands of minute, as well as large, diameters.

In forming drawing dies or tools of the type and kind under consideration, the entrance angle 50 or taper of the die must be constructed to suit the different uses to which the tool is adapted. With a machine of the type and kind under consideration, these tapers or entrance angles may be produced to the most accurate degree desirable, especially through a wide range adjustability, or

what may be termed flexibility, of the machine.

One of the distinctive features of the present invention resides in supporting the drills in a stationary or fixed position while rotating the drills at high speed in this position. A further feature resides in yieldably moving the workpieces toward and from the drills as well as in raising the position of the workpiece supports to provide a feed of the workpieces in the direction of the drilling tools in a successive series of operations.

In the accompanying drawings, 15 represents a suitable base upon which is supported a vertical column 16 having a reduced upper end portion 17. Adjustably supported on the column is a bracket 18 to one side of which is bolted an electric drive motor 19 with the shaft of the motor arranged vertically. The motor has an adjustable support 20 in another bracket 21 supported on the column 16. The bracket 18 has an extension 22 upon which is supported the bed or table 23 of the machine.

The shaft of the motor 19 has an extension 24 upon which are arranged a vertical drive pulley unit 25 and pulley 26 and three other pulleys 27, 28 and 29. The extension 24 may be supported in any desired manner, and in the construction shown, brackets 30 and 31 are indicated. The latter brackets are supported upon the extension 17 of the column 16. The bracket 31 is in turn supported upon a larger bracket 32 in the free end of which is arranged a drive shaft 33 actuated through stepped pulleys 34 which are driven from the pulley 29 through a belt 35.

The shaft 33 passes through a rack bushing 36 supported in the bracket 32 by which the shaft 33 may be raised and lowered in moving the tools out of engagement with the work for the replacement of the tools. The rack 36 is operated through a hand wheel 37 actuating a pinion 38 engaging the rack. An adjustable coupling link 39 is provided for coupling the shaft 33 with the extension 33a thereof. Keyed to the extension 33a is a large drive gear 40.

On the bed or table 23 is an upstanding spindle 41. Rotatable on this spindle is the turret or workpiece supporting table 42. The table 42 has an upwardly directed sleeve extension 43 upon which the downwardly directed sleeve extension 44 of a tool supporting table 45 is arranged. The latter carries circumferentially of the periphery thereof, tool supporting chucks 46 for the needles, drills or tools 47. The shafts or spindles of the chucks have gears 48 which mesh with the gear 40 to provide for a high speed drive of the tools 47. When quiet operation of the machine is desired, it is preferred that fibre gears 48 be employed, otherwise any other type of gears can be utilized. In the construction shown, twelve chucks 46 are employed, but it will be understood that any desired number of tools may be provided.

The tables 42 and 45 are bolted together by a plurality of bolts 49, note Fig. 3 of the drawings, so that the two tables will operate as a unit. It will be understood that in the upward movement of the tools 47 through the medium of the rack 36, the entire unit will move upwardly carrying with it the bushing 50 and the bearings disposed in this bushing.

A coupling plate 51 is fixedly secured to a shaft 33b which extends downwardly through the spindle 41. The plate 51 is secured to the bushing 50, whereas the lower end of the shaft 33a is riveted to seat in one of the bearings as at 52, note Fig. 14. The bearings are held in place by a plate

53 and spaced apart by a spacing sleeve 54. In other words, the shaft 33a is free to rotate within the bushing 50 without contributing any rotary movement to the shaft 33b.

The shaft 33b extends through the bracket extension 22, note Fig. 10, and is coupled with an enlarged threaded portion 55 which operates in a threaded bushing 56 keyed against rotation in a housing 57 by a screw 58, note Fig. 1. At this time it is to be understood that in the upward movement of the tools 47 through the rack 36, the screw 58 must be loosened to permit the bushing 56 to slide vertically. The housing 57 is supported in connection with the bracket extension 22 by bolts 59. An adjustment nut 60 is provided on the enlarged threaded extension 55 to limit downward movement of the drills in the workpiece. The screw 55 forms a feed screw which feeds the table 45 downwardly in the slow intermittent rotary movement thereof, as will be apparent. It will be understood that the table 45 slides on the bolts 49 which act as key pins in keying the tables 42-45 together. It will also be understood that there is sufficient flexure in the belt 35 to compensate for this movement.

The turret or table 42 is supported against movement on the spindle 41 by a plate 61 secured to the top of the spindle and overlapping the sleeve portion 43. By resting upon a bearing or collar 62 seating on an enlarged portion of the spindle 41, sufficient clearance is provided between the plates 51 and 61 to compensate for the automatic downward feed of the tools in the workpieces.

The chuck construction 46 is shown in sectional detail in Fig. 2 of the drawings, and at 46a is indicated a set screw for retaining the tools 47 in proper position of adjustment in these chucks. It will be understood, however, that any type or kind of chuck will be provided. While plain bearings are disclosed in the present chuck construction, it will be understood that any other mountings may be provided.

Supported directly beneath each of the chucks 46 in the table 45 are workpiece supporting members 63 arranged in the table 42. Each of these members comprise a sleeve or bushing 64 in which is disposed a plunger sleeve 65. Coupled to the lower end of the plunger sleeve 65 is a rod 66. Secured to the lower protruding end of the sleeve 64 are pins 67 to which are attached springs 68 coupled with cotter-pins or the like 68a which serve to support the sleeve in raised position in the table 42. The protruding end of the sleeve 64 is provided with slots 69 to receive an extending arm 70 on the lower end of the rod 66. Adjustable in the arm 70 is a screw 71, operating upon the lower end of a rod 72 which moves vertically in the table 42. The rod is keyed against rotation therein by a pin 73 operating in a slot 74. The upper end of the rod 72 has an inwardly directed extension 75 in connection with which an adjustable screw operates. The screw 76 adjustably clamps a block 77 in the forked end 78 of a rocker arm 79 pivoted as seen at 80. This adjustment is to increase or decrease the stroke or movement of the workpiece 81 toward and from the drilling tool 47. The other end 82 of the lever engages another pin 83 slidable in the table 42. The lower end of the pin 83 engages and is actuated by a wobble cam 84 which is supported upon a variable pulley unit 85. The unit 85 is rotatable upon the fixed spindle 41 and actuated through the variable pulley 25 and belt 25a.

The wobble cam 84 is shown in detail in Fig. 11 of the drawings. This cam has two downwardly extending arms 84a supporting fulcrum screws 84b which are fixedly supported in the variable pulley 85. Other set screws 84c are disposed at right angles to the screws 84b and adjustably engage the pulley to vary the inclination of the cam so as to govern the so-called wobble or cam-like action thereof to impart movement to the workpieces 81 as the cam is rotated through the pulley 85.

Supported on the top of the plunger 65 is a cup-shaped casing 86, note Fig. 2, which is adjustably supported on the plunger. Also supported within the plunger is a sleeve 87 in which is slidably mounted a rod 88 carrying at its upper end a supporting table 89 for the workpiece 81. A light spring 90 is disposed between the table 89 and the casing 86 to permit yieldable movement of the workpiece 81 in a direction away from the tool 87 when the workpiece is moved into engagement with the tool; thereby avoiding any possible jamming or destruction to the fine points of the tool and compensating for any irregularities which may prevail, and definitely eliminating a positive movement of the workpiece into engagement with the tool. The pin 88 is retained against upward movement by a key pin 91 operating in an elongated aperture 92 in the sleeve 87 which also keys the support 89 against rotation. The adjustment of the casing 86 will regulate the tension of the spring 90.

The workpiece 81 in the construction shown and as illustrated in part in Fig. 12 of the drawings has a diamond 81a mounted therein. The workpiece body is provided with beveled sockets or admission ports 81b and 81c opening into the diamond. The diamond is drilled preferably by the use of three or more drills having different degrees of grindings on the pointed ends thereof. In Fig. 13 of the drawings, the drill 47a is ground at substantially 45°, the drill 47b at substantially 30°, and the drill 47c at substantially 15°. It is the purpose to use these drills in a successive series of operations on one machine, or where several machines are employed, one drilling may be performed on one machine, the other on the next, and the third on the latter. If more stages of drillings are desired, other bevels will be provided on the tools for producing the desired results. The present illustration is solely for the purpose of giving an idea as to the procedure to be followed, and not to be regarded as a restriction or limitation of the machine operation. The diamond may be partially drilled on one side as indicated at 81d, whereas the final drillings to produce the final restricted area 81e may be performed in the three stages as indicated and as diagrammatically shown in Fig. 12 of the drawings.

Returning for a moment to the plunger 65, it will be seen upon a consideration of Fig. 2 of the drawings that a rather heavy spring 65a is employed to seat upon the lower end of the plunger and upon an air vented bushing 64a supported within the bushing 64 so as to provide a further yieldable backing for the plunger. The spring 65a also supports the plunger 65 in its upwardly extended position, and at the same time holds the pin 88 firmly upon the surface of the wobble cam 84. In other words, the plunger is actuated by the cam through the compression of the spring 65a. The adjustment of the screw 71 will control the position of the workpiece with respect to the

drilling tool as well as controlling the tension of the spring 65a.

Secured to the bushing 64 is a plate 93 which carries an anti-frictional roller 94. The plate 93 operates in a slot 95 formed in the sleeve extension of the table 42, note Fig. 9 of the drawings. The roller 94 operates upon a cam 96 to lower the workpiece 81 as well as the bushing 64 against the action of the spring 68, an appreciable distance away from the tool 47 in the grinding stage or position which is later described. In this operation the screw 71 will move away from the rod 72, and the bushing 64 is keyed against rotation by the plate 93 operating in the slot 95. The cam 96 is fixedly supported upon the stationary table or bed 23 as seen at 96a in Fig. 1 of the drawings.

It will be understood that throughout the operation of the machine, the tables 42 and 45 are intermittently rotated to bring successive units consisting of one workpiece and one drill, into what may be termed the grinding and lubricating stage which is represented at x in the upper corner portion of Fig. 3 of the drawings. To provide this intermittent feed of the tables, the periphery of the table 42 is provided with a series of teeth or projections 42a, note Fig. 3 of the drawings, adapted to be engaged by a pawl 97 pivoted to a ring 98. The ring 98 is supported upon the periphery of the table 42 and is intermittently rotated or oscillated circumferentially in a back and forth direction on the periphery of the table 42 by a link 99 coupled with the disc 98 as seen at 100 and with a crank disc 101. The latter is driven through a reduction unit from the pulley 26, the belt 26a of which passes around a pulley 26b mounted on the shaft 26c of said unit. The unit is in the form of a casing 102 supported upon the column 16 or the extension 17 thereof as will clearly appear in Fig. 3 of the drawings.

On the shaft 26c is a worm gear 103 operating a worm wheel 104 on a shaft 105. On the shaft 105 is a worm 106 operating a gear 107 on the shaft 108 to which the crank 101 is secured. It is preferred that a very high reduction be provided so as to provide a slow intermittent feed of the respective units to successively bring them into the grinding stage position as at x. It will be understood that as the disc 98 is rotated in one direction, the pawl 97 will pick up one of the teeth 24a, and in moving the disc 98 in the opposite direction, the tables 42-45 will be rotated one step. A spring 97a is employed to maintain the pawl in constant engaging position.

Supported on the undersurface of the disc 98 is a gear rack or segment 98a. This segment engages a gear 109 secured to a shaft 110 supported in a suitable housing 111. The shaft 110 has another gear 112 meshing with a long rack bar 113 slidably engaging the casing 111 and controlling a pick-up and feed of a lubricant and abrasive such as diamond dust as applied to each workpiece when the same is in the position x.

Supported in conjunction with the housing 111 is a long guide rail 114 having intermediate its ends an upwardly and inwardly extending supporting arm 115 carrying at its upper end a pan or a receptacle 116 for the lubricant abrasive compound. Supported upon the guide rail 114 is a slide 117 on which is pivotally supported as at 118 a pump cylinder 119. A pump piston or plunger 120 is coupled with an operating lever 121 which is pivoted to the free end of the rack 113. The lever 121 operates in a recessed por-

tion of the cylinder block, said recessed portion having two adjustable screws 122 and 123 to limit movement of the lever 121 in both directions.

Carried upon the outer end of the cylinder is a hook-shaped arm 124, the hook end 125 of which is adapted to pass beneath the lower surface of the rail to support the pump casing 119 in a position as indicated in Fig. 8 of the drawings. The pump cylinder assumes a position at the extreme end of the guide rail 114 substantially at the completion of the intermittent rotary movement of the tables 42 and 45. In this position, the pump cylinder is tilted in the position shown in Fig. 7 to dispose the nozzle end 126 of a pick-up and delivery tube 127 within the receptacle 116.

As the disc 98 is rotated through the crank employed, the rack 113 will be first moved to the right as viewed in Fig. 7, actuating the pump 120 to suck up a portion of compound from the receptacle. It will be understood in this connection that the tube 127 is filled or substantially filled with a lubricant or other fluid. When the lever 121 strikes the adjustable screw 123, the pump cylinder 129 will be tilted, thus raising the nozzle end 126 out of the receptacle and placing the hook end 125 beneath the guide rail 114. The slide 117 is now moved to the right on the slide 114 until it reaches the position indicated in Fig. 8. In this position, the nozzle end 126 is disposed directly above and centrally of the workpiece 81, and the disc 98 has completed its rotary oscillation in the non-feeding stroke.

Upon the beginning of the return or feed stroke of the disc or ring 98, the rack 113 will first move the lever 121 in the direction of the screw 122, thus advancing the piston 120 in the cylinder to forcibly discharge the drop or small portion of the lubricant abrasive compound into the bore of the diamond disposed within the workpiece 81. As the movement of the ring 98 continues, the slide 117 is moved to the left and returns to the position shown in Fig. 7, at the completion of which the pump cylinder is tilted to re-submerge the nozzle 126 in the receptacle 116, and the above cycle of operation is repeated.

During the time of actuating the pick-up and delivery of the lubricant and abrasive compound, which is performed while the tables 42-45 are at rest, each tool or drill 47 when in the position *x* and when the workpieces 81 have been lowered through the means previously described, the ends of the drills or tools are ground automatically by a grinding wheel 128 which is mounted upon a rotatable and vertically oscillating shaft 129 supported in a suitable housing 130. The housing 130 is adjustable upon a bracket plate 131 to vary the angularity or inclination of the grinding wheel with respect to the tool, to grind the various tapers on the pointed ends thereof, as indicated in Fig. 13 of the drawings. This adjustment may be gaged by a scale 131a provided on the surface of the plate 131 registering with a pointer 132 supported upon a fixed bracket member 133 secured to the column 16. The plate 131 is pivoted on the bracket 133 as seen at 133a, and held in different positions of adjustment by a bolt 133b operating in an elongated slot 133c. This plate has a series of longitudinal dove-tailed grooves 134 in which headed bolts 135 are mounted, the latter being carried by the housing 130.

The shaft 129 is driven from the pulley 28 and a belt 28a passing around a pulley 129a on said shaft so as to rotate the grinding wheel 128 at 75

relatively high speed. At the same time it is desirable to move the shaft longitudinally in its support. This is accomplished by the rotation of an eccentric 136 supported in the housing 130 and actuating a crank 137 coupled with a lever 138 pivoted as seen at 139 to the housing and coupled with the shaft 129 as seen at 140. The eccentric is actuated from the pulley 27, the belt 27a and a pulley 141, the latter mounted on a shaft 142 supported in the housing 130. On the shaft 142 is a worm 143 which meshes with a worm wheel 144 on the shaft of the eccentric 136. The reciprocating movement of the grinding wheel 128 over the tool is relatively slow as compared with the rotary movement imparted to said wheel.

The grinding wheel 128 is supported in a housing 145 having a suction extension as at 146 whereby a suction pipe may be employed to draw the grinding away from the machine as will be apparent.

The housing 145 has a bracket portion 147 keyed in the slots 134 of the plate 131 and held in different positions of adjustment by a bolt 148, note Fig. 4. Supported in an extension 145a of the housing 145 are two adjustable screws 149 and 150, the screw 149 carrying on its inner end a diamond or other trimming tool 151 for re-surfacing the wheel 128. On the screw 149 is a gear 152 having spaced apertures 153 for a spanner or other wrench, by means of which the gear 152 may be rotated to feed the screw 149 in advancing the tool 151 in the direction of the grinding wheel 128.

At 154 is a larger gear in operative engagement with the gear 152 through an intermediate gear 155, so that the gear 154 is rotated at twice the speed of the gear 152 to feed the screw 150 a distance twice that of the feed of the tool 151, so as to bring the housing 145 in proper position, compensating for the re-surfacing of the wheel 128. In this operation, the bolt 148 is loosened to provide the said movement of the housing 145.

It will of course be understood that the re-surfacing of the grinding wheel 128 is performed only when occasions require the same. Therefore, this operation is not automatic but is rather under manual control.

In the above described operation with respect to each of the drilling units, it will be understood that all of the units are actuated simultaneously except from the standpoint of the feed of the workpieces toward and from the drill which is controlled through the operation of the wobble cam which operates at relatively high speed. These units move around and successively come into the grinding stage or position as at *x*, and when in this position, the workpiece including its support is moved downwardly through the action of the cam 96 and supported in this position while the grinding wheel is operating upon the tool then supported in this position. It will be understood that the tool is revolved at the same speed as the grinding wheel is rotated over the surface of the tool to re-grind or sharpen the same preparatory to another cycle of operation, or in other words, until this tool again returns to the grinding stage as at *x*.

The dropping of the lubricant and abrasive into the workpiece at this particular stage provides the necessary supply of lubricant and abrasive to last until the workpiece again returns to the stage or position as at *x*.

After a series of these operations have been

performed, the workpieces will have been drilled to the desired extent, and from time to time an operator may remove the workpieces to check upon the drilling operations performed therein.

A suitable switch 156, note Fig. 1, is provided on the table 23 to electrically control the stopping and starting of the motor 19, particularly in the setting of new drills in position in the machine as well as in replacing workpieces.

It will be understood that while I have illustrated my machine as being adaptable for use in the drilling of diamonds in producing what are known as drawing dies, that the machine is adaptable for use in drilling any type and kind of workpieces where it is desirable to maintain the drill in fixed position while rotating at a high speed and in yieldably moving the workpiece to be drilled toward and from the drill. It will of course be apparent that the particular number of drill units employed on a machine may be varied and the degree of automatic feed of the workpiece in the direction of the drills may also be varied in machines of different types and kinds, the illustration in the accompanying drawings being understood to represent one adaptation of the invention.

In the operation of my improved machine it will be understood that one of the distinctive characteristics of the machine resides in the fact that the tools 47 are mechanically and automatically moved in the direction of the die or workpiece during each cycle of revolution of the table 45 through the medium of the feed screw 55. By virtue of this construction, and further by reason of the fact that the spacing of the workpiece or die 81 with respect to the tool 47 is adjustable, it is possible to so regulate the machine that the first relative movement of the tool with respect to the workpiece may be so minute as to barely touch the workpiece or in fact may not engage the workpiece, but in each successive position of the tool and workpiece, as the table is rotated, the tool is brought in closer relationship to the workpiece in minute degrees. This construction and method of procedure eliminates the collapsing of the pointed ends of the tool and eliminates the formation of heads on these ends which commonly occurs in other apparatus of this type and kind by reason of an excessive blow between the tool and the workpiece, the result of which is to flatten or head the pointed end of the tool, or in some cases to break off or destroy this pointed end. In the automatic operation of the machine, it will also be apparent that after having completed one cycle of operation, each tool is then reground to sharpen the pointed end before starting the next cycle of operation. This regrounding is consistent with and compensates for the downward feed of the table and maintains a constant relationship of the tool with the workpiece as formed at any particular stage in the cycle, thus bringing the tools deeper and deeper into the workpiece or die until the desired drilling operation has been performed. As previously set forth, this may be through a series of stages in forming the different angles as diagrammatically illustrated in Fig. 12, it being understood that the comparative relative degrees may be varied to suit different types and kinds of workpieces. It will also be apparent that the independent adjustability of each workpiece support and operating member provides for the independent control and regulation of each workpiece and the tool operating in conjunction therewith.

Having fully described my invention, what I

claim as new and desire to secure by Letters Patent, is:

1. A machine of the class described comprising a pair of intermittently rotatable members coupled together for simultaneous movement, one member supporting a plurality of drill chucks with means adjustably supporting drills therein, the other member having a plurality of yieldable workpiece supporting elements disposed in vertical alinement with said chucks, means automatically rotating the drills at high speed, means for intermittently moving workpieces supported on said elements toward and from said drills in the operation of drilling the workpieces, means intermittently rotating said members step by step to bring, in one complete cycle of operation, all of the drills and workpieces into one predetermined position, means at said predetermined position for moving each workpiece away from the companion drill, and means at said predetermined position for automatically grinding the end of a drill supported at said position to sharpen the same.

2. A machine of the class described comprising a pair of intermittently rotatable members coupled together for simultaneous movement, one member supporting a plurality of drill chucks with means adjustably supporting drills therein, the other member having a plurality of yieldable workpiece supporting elements disposed in vertical alinement with said chucks, means automatically rotating the drills at high speed, means for intermittently moving workpieces supported on said elements toward and from said drills in the operation of drilling the workpieces, means intermittently rotating said members step by step to bring, in one complete cycle of operation, all of the drills and workpieces into one predetermined position, means at said predetermined position for moving each workpiece away from the companion drill, and means at said predetermined position for automatically grinding the end of a drill supported at said position to sharpen the same, and means automatically delivering a lubricant abrasive compound to the workpiece while in said predetermined position.

3. A machine of the class described comprising a pair of intermittently rotatable members coupled together for simultaneous movement, one member supporting a plurality of drill chucks with means adjustably supporting drills therein, the other member having a plurality of yieldable workpiece supporting elements disposed in vertical alinement with said chucks, means automatically rotating the drills at high speed, means for intermittently moving workpieces supported on said elements toward and from said drills in the operation of drilling the workpieces, means intermittently rotating said members step by step to bring, in one complete cycle of operation, all of the drills and workpieces into one predetermined position, means at said predetermined position for moving each workpiece away from the companion drill, and means at said predetermined position for automatically grinding the end of a drill supported at said position to sharpen the same, means automatically delivering a lubricant abrasive compound to the workpiece while in said predetermined position, and means automatically feeding one of said members in the direction of the other member during successive cycles of rotation of both of said members to feed the drills a greater depth into the workpieces.

4. A machine of the class described comprising a pair of intermittently rotatable members

coupled together for simultaneous movement, one member supporting a plurality of drill chucks with means adjustably supporting drills therein, the other member having a plurality of yieldable workpiece supporting elements disposed in vertical alignment with said chucks, means automatically rotating the drills at high speed, means for intermittently moving workpieces supported on said elements toward and from said drills in the operation of drilling the workpieces, means intermittently rotating said members step by step to bring, in one complete cycle of operation, all of the drills and workpieces into one predetermined position, means at said predetermined position for moving each workpiece away from the companion drill, means at said predetermined position for automatically grinding the end of a drill supported at said position to sharpen the same, means automatically delivering a lubricant abrasive compound to the workpiece while in said predetermined position, means automatically feeding one of said members in the direction of the other member during successive cycles of rotation of both of said members to feed the drills a greater depth into the workpieces, and adjustable means limiting the inward feed of the drills.

5. A machine of the class described comprising a pair of intermittently rotatable members coupled together for simultaneous movement, one member supporting a plurality of drill chucks with means adjustably supporting drills therein, the other member having a plurality of yieldable workpiece supporting elements disposed in vertical alignment with said chucks, means automatically rotating the drills at high speed, means for intermittently moving workpieces supported on said elements toward and from said drills in the operation of drilling the workpieces, means intermittently rotating said members step by step to bring, in one complete cycle of operation, all of the drills and workpieces into one predetermined position, means at said predetermined position for moving each workpiece away from the companion drill, means at said predetermined position for automatically grinding the end of a drill supported at said position to sharpen the same, means automatically delivering a lubricant abrasive compound to the workpiece while in said predetermined position, means automatically feeding one of said members in the direction of the other member during successive cycles of rotation of both of said members to feed the drills a greater depth into the workpieces, adjustable means limiting the inward feed of the drills, and means for manually raising the drill chucks for the replacement or re-setting of drills therein.

6. A machine of the class described comprising a pair of intermittently rotatable members coupled together for simultaneous movement, one member supporting a plurality of drill chucks with means adjustably supporting drills therein, the other member having a plurality of yieldable workpiece supporting elements disposed in vertical alignment with said chucks, means automatically rotating the drills at high speed, means for intermittently moving workpieces supported on said elements toward and from said drills in the operation of drilling the workpieces, means intermittently rotating said members step by step to bring, in one complete cycle of operation, all of the drills and workpieces into one predetermined position, means at said predetermined position for moving each workpiece away

from the companion drill, means at said predetermined position for automatically grinding the end of a drill supported at said position to sharpen the same, and means adjustably supporting the last named means to vary the angularity of the grinding of said drills.

7. A machine of the class described comprising a pair of intermittently rotatable members coupled together for simultaneous movement, one member supporting a plurality of drill chucks with means adjustably supporting drills therein, the other member having a plurality of yieldable workpiece supporting elements disposed in vertical alignment with said chucks, means automatically rotating the drills at high speed, means for intermittently moving workpieces supported on said elements toward and from said drills in the operation of drilling the workpieces, means intermittently rotating said members step by step to bring, in one complete cycle of operation, all of the drills and workpieces into one predetermined position, means at said predetermined position for moving each workpiece away from the companion drill, means at said predetermined position for automatically grinding the end of a drill supported at said position to sharpen the same, means automatically delivering a lubricant abrasive compound to the workpiece while in said predetermined position, means automatically feeding one of said members in the direction of the other member during successive cycles of rotation of both of said members to feed the drills a greater depth into the workpieces, and adjustable means limiting the inward feed of the drills.

8. A machine of the class described comprising a pair of intermittently rotatable members coupled together for simultaneous movement, one member supporting a plurality of drill chucks with means adjustably supporting drills therein, the other member having a plurality of yieldable workpieces supporting elements disposed in vertical alignment with said chucks, means automatically rotating the drills at high speed, means for intermittently moving workpieces supported on said elements toward and from said drills in the operation of drilling the workpieces, means intermittently rotating said members step by step to bring, in one complete cycle of operation, all of the drills and workpieces into one predetermined position, means at said predetermined position for moving each workpiece away from the companion drill, means at said predetermined position for automatically grinding the end of a drill supported at said position to sharpen the same, said last named means comprising a grinding wheel, and means for intermittently resurfacing said grinding wheel.

9. In a drilling machine of the class described, a workpiece drilling mechanism comprising a drill supporting chuck, means for rotating said chuck, a workpiece supporting unit disposed in alignment with said chuck, said unit comprising a bushing, a tubular plunger slidably mounted in the bushing, a workpiece supporting part yieldably supported in said plunger, means limiting movement of said part in the direction of the drill chuck, and means moving said part intermittently toward and from the drill chuck.

10. In a drilling machine of the class described, a workpiece drilling mechanism comprising a drill supporting chuck, means for rotating said chuck, a workpiece supporting unit disposed in alignment with said chuck, said unit comprising a bushing, a tubular plunger slidably mounted in the bushing, a workpiece supporting part yieldably supported in said plunger, means limiting movement of said part in the direction of the

drill chuck, means moving said part intermittently toward and from the drill chuck, and means yieldably supporting the plunger in said bushing.

11. In a drilling machine of the class described, a workpiece drilling mechanism comprising a drill supporting chuck, means for rotating said chuck, a workpiece supporting unit disposed in alinement with said chuck, said unit comprising a bushing, a tubular plunger slidably mounted in the bushing, a workpiece supporting part yieldably supported in said plunger, means limiting movement of said part in the direction of the drill chuck, means moving said part intermittently toward and from the drill chuck, means yieldably supporting the plunger in said bushing, and means for moving the unit away from said chuck to space the workpiece from a drill supported in said chuck.

12. In a drilling machine of the class described, a workpiece drilling mechanism comprising a drill supporting chuck, means for rotating said chuck, a workpiece supporting unit disposed in alinement with said chuck, said unit comprising a bushing, a tubular plunger slidably mounted in the bushing, a workpiece supporting part yieldably supported in said plunger, means limiting movement of said part in the direction of the drill chuck, means moving said part intermittently toward and from the drill chuck, means yieldably supporting the plunger in said bushing, and means automatically feeding the chuck in the direction of said unit throughout a series of drilling operations.

13. The combination with a drilling machine having a drill supporting chuck with means for rotating the chuck and a drill supported therein at high speed, of a workpiece supporting unit comprising a yieldably supported plunger arranged in axial alinement with said drill chuck, means for intermittently moving the plunger toward and from the drill chuck, a workpiece supporting part having a yieldable mounting in said plunger to provide yieldable engagement of a workpiece arranged on said part with a drill disposed in said chuck independent of the yielding support for said plunger, and means adjustable on the plunger for varying the yielding support for said part.

14. The combination with a drilling machine having a drill supporting chuck with means for rotating the chuck and a drill supported therein at high speed, of a workpiece supporting unit comprising a yieldably supported plunger arranged in axial alinement with said drill chuck, means for intermittently moving the plunger toward and from the drill chuck, a workpiece supporting part having a yieldable mounting in said plunger to provide yieldable engagement of a workpiece arranged on said part with a drill disposed in said chuck independent of the yielding support for said plunger, means adjustable on the plunger for varying the yielding support for said part, and means for moving said plunger and part in wide spaced relationship away from a drill supported in said chuck.

15. A drilling machine of the class described comprising a vertical column, a fixed bed plate disposed at one side of the column, means supporting a motor at the opposite side of the column with the shaft of the motor arranged parallel to the column, a spindle on said bed plate, two coupled discs rotatably mounted on the spindle, means intermittently rotating the discs step by step to bring vertically alined drilling units

successively into predetermined position, each unit comprising a drill rotated at high speed and a yieldable workpiece support intermittently moved toward and from the drill in the rotation thereof, means simultaneously rotating the drills of all of said units, means for actuating the workpiece supports, and means for automatically feeding the drills in the direction of the workpiece supports throughout a series of intermittent rotary movements of said discs.

16. A drilling machine of the class described comprising a vertical column, a fixed bed plate disposed at one side of the column, means supporting a motor at the opposite side of the column with the shaft of the motor arranged parallel to the column, a spindle on said bed plate, two coupled discs rotatably mounted on the spindle, means intermittently rotating the discs step by step to bring vertically alined drilling units successively into predetermined position, each unit comprising a drill rotated at high speed and a yieldable workpiece support intermittently moved toward and from the drill in the rotation thereof, means simultaneously rotating the drills of all of said units, means for actuating the workpiece supports, means for automatically feeding the drills in the direction of the workpiece supports throughout a series of intermittent rotary movements of said discs, means automatically lowering the workpiece supports when in said predetermined position to give free access to the drill of said unit, a grinding wheel arranged in said predetermined position for engaging the drill, and means for rotating said wheel and for moving the same longitudinally of the pointed end of the drill in the operation of grinding the same.

17. A drilling machine of the class described comprising a vertical column, a fixed bed plate disposed at one side of the column, means supporting a motor at the opposite side of the column with the shaft of the motor arranged parallel to the column, a spindle on said bed plate, two coupled discs rotatably mounted on the spindle, means intermittently rotating the discs step by step to bring vertically alined drilling units successively into predetermined position, each unit comprising a drill rotated at high speed and a yieldable workpiece support intermittently moved toward and from the drill in the rotation thereof, means simultaneously rotating the drills of all of said units, means for actuating the workpiece support, means for automatically feeding the drills in the direction of the workpiece supports throughout a series of intermittent rotary movements of said discs, means automatically lowering the workpiece supports when in said predetermined position to give free access to the drill of said unit, a grinding wheel arranged in said predetermined position for engaging the drill, means for rotating said wheel and for moving the same longitudinally of the pointed end of the drill in the operation of grinding the same, and means adjusting the angular position of said grinding wheel to regulate the angularity or taper of the pointed end of said drill.

18. A drilling machine of the class described comprising a vertical column, a fixed bed plate disposed at one side of the column, means supporting a motor at the opposite side of the column with the shaft of the motor arranged parallel to the column, a spindle on said bed plate, two coupled discs rotatably mounted on the spindle, means intermittently rotating the discs step by step to bring vertically alined drilling units

successively into predetermined position, each unit comprising a drill rotated at high speed and a yieldable workpiece support intermittently moved toward and from the drill in the rotation thereof, means simultaneously rotating the drills of all of said units, means for actuating the workpiece supports, means for automatically feeding the drills in the direction of the workpiece supports throughout a series of intermittent rotary movements of said discs, means automatically lowering the workpiece supports when in said predetermined position to give free access to the drill of said unit, a grinding wheel arranged in said predetermined position for engaging the drill, means for rotating said wheel and for moving the same longitudinally of the pointed end of the drill in the operation of grinding the same, means adjusting the angular position of said grinding wheel to regulate the angularity or taper of the pointed end of said drill, means involving spaced drives longitudinally of the motor shaft for rotating the drills, operating the workpiece support, intermittently rotating said discs, rotating the grinding wheel and for moving said wheel longi-

tudinally of the drill, and means in operative engagement with the automatic feed of said discs for delivering a lubricant grinding compound to workpieces arranged on said supports when in said predetermined and lowered position.

19. A drilling machine of the class described comprising circumferentially arranged and spaced drill supporting chucks, means adjustably supporting drills in said chucks, a plurality of 10 workpiece supporting members arranged in alignment with said drill chucks and yieldable toward and from said drill chucks, means for collectively rotating said drill chucks and workpiece supporting members in a successive series of intermittent 15 movements in each complete cycle of rotation of said chucks and members with respect to a predetermined position, means for slowly feeding the drill chucks in the direction of said members in the intermittent rotary movement imparted thereto to slowly feed the drills into workpieces supported in said members, and means for rotating drills supported in said chucks at high speed.

AARON SIMONS.
